(57) **CLAIM**

The ornamental design for a compressed air dryer, as shown and described.

DESCRIPTION

FIG 1. Is a perspective view of a compressed air dryer showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines show portions of the design that form no part of the claimed design.
